ADJUSTABLE SLITTER FOR PRINTING
PRESSES AND THE LIKE

John A. Davidson, Brooklyn, N. Y.

Application February 28, 1941, Serial No. 381,187

2 Claims. (Cl. 164—70)

This invention relates to slitters and perforators particularly adapted for use on printing presses of the off-set type and the like.

When sheets are being printed on presses of the indicated type, it is preferred to slit or perforate said sheets as they pass over the impression cylinder. In accomplishing this operation, great care must be exercised not to injure the cylinder by scoring or in any other manner. Also great difficulty is encountered in positioning the slitter or perforator with respect to the printed sheet and this difficulty is magnified when several such devices are simultaneously employed.

The invention, therefore, has for its primary object the provision of a slitter or perforator which can be micrometrically positioned so as to slit or perforate accurately along the line desired and with an exact degree of pressure whereby proper slitting or perforating is had without danger to the impression cylinder.

Another object of the invention is to provide a slitting or perforating device which may be roughly positioned with respect to the impression cylinder of a press and then micrometrically and accurately adjusted to operate along a designated line and at a proper pressure.

The invention is further characterized by the simplicity of its structure, the ease with which it may be applied to a press, and assurance that, once set, it will maintain its position until readjusted.

With the foregoing and many other objects, features, and advantages in mind reference is now made to the accompanying drawing in which a preferred embodiment of the invention is illustrated, the following specification being based thereon.

In the drawing:

Fig. 1 is a plan view of a slitter or perforator incorporating the features of the invention, and shown partly in cross-section;

Fig. 2 is a side view thereof; and

Fig. 3 is a fragmentary detail sectional view as taken on the line 3—3 of Fig. 2.

Presses of the indicated type are provided with a member 5 in the form of a rod or tube which is positioned in spaced relation to the impression cylinder shown at 6.

The slitting or perforating device, as at present contemplated, comprises a housing 7 arranged to be clamped on the bar 5 as by means of the clamp member 8 pivotally connected to said housing at 9 and locked by the screw or bolt means 10.

The housing 7 is preferably formed with a

slideway 11 for a cutter holding unit 12 which is longitudinally movable therethrough. The cutter holding unit may comprise the slide 13 at one end of which is rotatably mounted a cutter 14 which may be a slitter or perforator, and which is provided at the other end with a threaded stud 15. The latter portion preferably protrudes through an opening 16 formed in a wall 17 of the housing 7. A compression spring 18 or other suitable means may be arranged around the stud 15 and confined between the wall 17 and the slide 13 to urge the cutter holding unit in a direction towards the impression cylinder 6.

In order to control the longitudinal position 15 of the cutter holding unit and for accurately locating the edge of the cutter 14 with respect to the surface of the impression cylinder, an adjusting nut 19 is provided. This nut is preferably made in the form of a hand manipulatable member having a threaded seat 20 for the stud 15 and held by the spring 18 against the housing wall 17. In order to obviate creeping of the nut 19 and to provide a means for determining the end-wise adjusting movement of the 20 cutter holding unit, a detent 21 having successive 25 engagement with a plurality of circumferentially arranged depressions 22, which are formed in the housing wall 17 is provided.

It may be seen from the foregoing that the 30 edge of the cutter may be accurately positioned with respect to the impression cylinder to give a desired degree of cutting pressure, and that, knowing the pitch of the screw thread on the stud 15, and counting the clicks of the detent, the forward or retracting movement of the cutter may 35 be accurately ascertained so that the adjusted position of the cutter may be known. If desired, a scale may be provided to disclose both the movement of the cutter with respect to the housing or 40 of the impression cylinder and the rotational movement of the nut 19. Thus, in the manner of a micrometer, an accurate reading of the cutter position with respect to the surface of the impression cylinder may be had.

45 The device is also provided with means for adjusting the cutter to a desired position along the length of the impression cylinder. For this purpose there is preferably provided a rack 23, which by means of clamps 24 may be secured to the bar 5. The rack, in this manner may be roughly 50 positioned.

The housing 7 is provided with a worm 25 or other suitable member having engagement with the rack 23, said worm being disposed in a bore 55 26 in said housing and said rack being preferably

relatively movable in a passage 27 formed therein. The worm 25 may be provided with extensions having bearing in the housing, and one or both of said extensions may be further extended as at 28 and formed for cooperative engagement with an adjusting tool for rotating said worm.

In order to accurately locate the cutter along the impression cylinder, the clamp 8 is eased by loosening the screw or bolt means 10 to free the slide housing for longitudinal movement along the tube 5. A suitable tool is then applied to the extension 28 to rotate the worm 25 which, because of its engagement with the rack 23, causes traverse of the housing 7 along the bar 5. When the cutter 14 is accurately positioned along a desired point of the impression cylinder, the clamp 8 is tightened and the tool removed.

From the foregoing it is evident that a simple and highly efficient device has been provided for universal adjustment of a slitting, piercing or perforating cutter. However, the principles of the invention as herein disclosed may be incorporated in structures varying in arrangement and proportion from the illustrated form of the invention without departing from the spirit and scope of the invention as hereinafter claimed.

Having thus described my invention what I claim as new, and desire to secure by Letters Patent, is:

1. A device of the character described comprising a housing having a slideway and a plurality of circumferentially-arranged depressions, a member adapted for movement in said slideway, a cutter on said member, means engaged between said housing and said member for urging said cutter in a direction away from said housing, screw means, manually operable means attached to said screw means for drawing said member and said cutter towards said housing, and means associated with said manually-operable means adapted for successive engagement with said depressions.

2. A device of the character described comprising a housing having a slideway and a plurality of circumferentially-arranged depressions, a member adapted for movement in said slideway, a cutter on said member, means engaged between said housing and said member for urging said cutter in a direction away from said housing, screw means, manually operable means attached to said screw means for drawing said member and said cutter towards said housing, said screw means comprising a threaded stud carried by said member, a nut engaged with said stud and detent means between said nut and said housing adapted for successive engagement with said depressions for maintaining said nut in adjusted position.

JOHN A. DAVIDSON.
